(57) **CLAIM**

The ornamental design for a capsulorhexis forceps, as shown and described.

DESCRIPTION

FIG. 1 is a perspective view of a capsulorhexis forceps, showing our design;

FIG. 2 is a top view of the subject design in FIG. 1;

FIG. 3 is a left-side view of the subject design in FIG. 1, the right-side view being a mirror image thereof;

FIG. 4 is a bottom view of the subject design in FIG. 1;

FIG. 5 is a rear view of the subject design in FIG. 1; and, FIG. 6 is a front view of the subject design in FIG. 1.
